UNITED STATES PATENT OFFICE.

WILLIAM E. SNEDIKER, OF CAMDEN, NEW JERSEY.

WRENCH.

SPECIFICATION forming part of Letters Patent No. 758,568, dated April 26, 1904.

Application filed May 29, 1903. Serial No. 159,283. (No model.)

To all whom it may concern:

Be it known that I, WILLIAM E. SNEDIKER, a citizen of the United States, residing at Camden, in the county of Camden and State of New Jersey, have invented certain new and useful Improvements in Wrenches, of which the following is a specification.

My invention relates to improvements in quick-adjusting wrenches, and particularly to wrenches in which is used a toggle-pawl between the fixed and movable jaws.

The object of my invention is to simplify the construction of a wrench by reducing the number of parts and to form said parts in such a manner that they may be quickly assembled.

A still further object of my invention is to construct the fixed head of the wrench so that the toggle-pawl may be held in position without a pivot-pin, which tends to weaken the parts.

A still further object of my invention is to make the fixed head in one piece with the handle and so forming said head that the movable jaw will be fulcrumed in said head instead of having the head pivoted to the handle, as has been done heretofore.

Referring to the drawings, Figure 1 is a longitudinal sectional view of a wrench, showing my invention embodied therein. Fig. 2 is a view similar to Fig. 1, showing the parts in a different position, as when clamping an object. Fig. 3 is a sectional view of the head of the wrench, showing the parts detached. Fig. 4 is a sectional view, as on line 4-4, Fig. 3. Fig. 5 is a sectional view, as on line 5-5, Fig. 3.

In the drawings, A represents the handle, having at one end a head B formed thereon, said head being made in one piece with said handle.

C represents a sliding bar carrying the movable jaw C', in which is provided the teeth C², which latter are adjacent to teeth B' in the fixed jaw B², secured in the head B. The said sliding bar C is T shape in cross-section, having the projecting portions C³ and C⁴, as shown in Fig. 4. Said projections are strengthened by fillets C where they join the head C'.

In the head B is formed an aperture B³, as shown in Fig. 5, to receive the sliding bar C.

Grooves B⁴ are provided for the projections C³ and C⁴ of the sliding bar C. Said sliding bar rests on the shoulders B⁶, and it is fulcrumed at the point B⁷, so that the head of the wrench and said sliding bar may take the 55 positions shown in Fig. 2, when sufficient force is placed on the handle A to force the teeth of the jaws into the object to be acted upon, so that said teeth will not slip on said object. 60

In the head of the wrench is formed a recess or socket B⁸. (Clearly shown in Figs. 3 and 4.) In this socket fits the head D' of the toggle-pawl D, which simply rests in said socket and is held in position by the end of 65 the spring b contacting with the shoulder d of the toggle-pawl. Teeth D² are provided on the upper surface of said toggle-pawl, which engage teeth C³ in the lower surface of the sliding bar C. The spring b holds said 70 toggle-pawl up against said sliding bar.

The toggle-pawl D is held up with sufficient force to slightly raise the inner end of the sliding bar up off the shoulders B⁶, so that the upper surface of said sliding bar will contact with the spring b³. It will thus be seen that by the action of the two springs b and b³ the teeth D² and C³ will remain in engagement. When the handle D³ of the toggle-pawl is depressed, the sliding bar C will rest 75 on the shoulders B⁶ and slide free of the toggle-pawl and also free of the action of the spring b³, as the end of the spring b³ is held by shoulders B⁹, so that it cannot follow the top of the sliding bar and bind the same. 80 Said spring b³ will yield sufficiently to allow the sliding bar and the head B to take the position shown in Fig. 2. 85

The fulcrum B⁷, upon which the sliding bar C moves, is formed as closely as possible to 90 the center of the socket B⁸, in which the head of the toggle-pawl rests. This construction will allow the fixed head and sliding bar to move in relation to each other without changing the distance between the head of the toggle-pawl and the sliding bar, the result being to keep the teeth of the toggle-pawl in perfect engagement with the teeth in the sliding bar. 95

The grooves B⁴ are narrow at the fulcrum- 100

point B⁷ and wider at the outer ends, so that the sliding bar C may rock on said fulcrum-point. The shoulders forming the grooves B⁴ do not bind the projections C³ and C⁴ of the 5 sliding bar at the inner end when the jaws of the wrench are in action. The entire strain comes on the toggle-pawl and the fulcrum B⁷. By this arrangement of the parts the necessity of having the head of the wrench pivoted 10 to the handle is avoided.

A pin C⁵ is placed in the end of the sliding bar to keep the sliding bar from dropping through the head of the wrench when the toggle-pawl is depressed. When it is desired to 15 take the wrench apart, said pin is removed and the sliding bar withdrawn from the head. By raising the handle D³ of the toggle-pawl the spring b will disengage the shoulder d on the toggle-pawl, and the said toggle-pawl may 20 be withdrawn from the socket B⁸.

Having thus described my invention, I claim and desire to secure by Letters Patent—

1. In a wrench the combination of a fixed head, a movable head, a sliding bar carrying 25 said movable head, a projection on either side of said sliding bar, shoulders formed on the interior of the fixed head, said shoulders forming a fulcrum and guides for said sliding bar, and a toggle-pawl acting between said fixed 30 head and said sliding bar substantially as described.

2. In a wrench the combination of a fixed head, a sliding bar carrying the movable head, shoulders formed in said fixed head adapted 35 to engage projections on either side of said sliding bar, a spring to hold said sliding bar down on said shoulders, a toggle-pawl, and a spring adapted to hold said toggle-pawl in engagement with said sliding bar, substantially 40 as described.

3. In a wrench the combination of a fixed head, a movable head, a sliding bar carrying said movable head, projections on either side of said sliding bar, shoulders in the fixed head to receive said projections, a spring to act 45 upon the upper surface of said sliding bar, shoulders formed in said fixed head to limit the movement of said spring, a toggle-pawl carried by said fixed head, and a spring adapted to hold said toggle-pawl in engagement with 50 said sliding bar, substantially as described.

4. In a wrench the combination of a fixed head, a movable head, a sliding bar carrying said movable head, a projection on either side of said sliding bar, shoulders formed on the 55 interior of the fixed head, said shoulders forming a fulcrum and guides for said sliding bar, a toggle-pawl pivoted in said fixed head adjacent to said fulcrum so that said sliding bar can rock on said fulcrum without changing 60 the relation between the toggle-pawl and the sliding bar, substantially as described.

5. In a wrench the combination of a fixed head, a movable head, a sliding bar carrying said movable head, a projection on either side 65 of said sliding bar, shoulders formed on the interior of the fixed head, said shoulders forming a fulcrum and guides for said sliding bar, and a toggle-pawl having a shoulder engaged by a spring in the fixed head, said spring 70 adapted to hold said toggle-pawl in position and also to keep the same in engagement with said sliding bar, substantially as described.

In testimony whereof I affix my signature in presence of two witnesses.

WILLIAM E. SNEDIKER.
